UNITED STATES PATENT OFFICE.

LEWIS AUGUSTUS ASPINWALL, OF JACKSON, MICHIGAN, ASSIGNOR TO ASPINWALL MANUFACTURING COMPANY, OF JACKSON, MICHIGAN, A CORPORATION OF MICHIGAN.

POTATO-PLANTER.

No. 864,595.

Specification of Letters Patent.

Patented Aug. 27, 1907.

Application filed April 9, 1906. Serial No. 310,601.

To all whom it may concern:

Be it known that I, LEWIS AUGUSTUS ASPINWALL, a citizen of the United States, residing at Jackson, in the county of Jackson and State of Michigan, have invented an Improvement in Potato-Planters, of which the following is a specification.

My present invention relates to improvements upon the devices shown and described in Letters Patent heretofore granted to me for improvements in potato-planters and especially to the devices shown and described in my Letters Patent No. 658,562, dated September 25, 1900.

The object of my present invention is to make more fully efficient the structure heretofore employed by me and to obviate difficulties which experience has brought to light so that the automatic and successful planting of potatoes by machinery may be more perfectly performed.

In the device of my present invention I employ a sack hopper suitably connected at its upper end to a metal frame for support, and as the said hopper is flexible it prevents the tendency of the potatoes to bridge in the hopper, and I prefer to employ two of these sack hoppers the same coming at opposite sides of central spring-held concaves through which the pickers move and which concaves and pickers are clearly shown and described in my aforesaid patent. In connection with these sack hoppers I employ devices permitting the progressive descent by gravity of the potatoes in the hoppers. These are feeding devices in the nature of plates constituting gates which press against the inner surfaces of the sack hoppers and serve to agitate the same; said gates being in turn mounted upon a rocker bar and actuated by a toggle and pivoted connecting rod from the axle of the machine. With these devices I employ a regulating thumb screw, the operation of which is to change the relation of the toggle and the connecting bar to the gate or to straighten the toggle so that more or less motion may be imparted to the gates, and I employ a spring connected at one end to the fixed seat post and at its other end to one end of the toggle. The spring serves to hold the gate in position and at the lower end of said gates I employ gravity members whose function is a retarding action on the out-flowing of the potatoes from the sack hoppers.

In my present invention I obviate the tendency of the potatoes to lodge between the disk supports of the pickers by providing low cut heads secured to a sleeve about the axle and place pickers in alternate series so that there is no opportunity for the potatoes to lodge between the parts.

For the purpose of regulating the delivery to the soil of potatoes from the hopper and for changing the speed of delivery I employ a series of gears, one of

which is fast upon the axle of the machine and one of which is secured to a loosely mounted main wheel; said gears meshing with others superimposed upon a stud of the frame.

For the purpose of applying the power more conveniently for the operation of the coverers I employ a spring actuated lever device.

I have found that in certain places the rows of potatoes are planted much closer together than in other places and to prevent the horses walking on the ridge of the previously planted row, I employ devices for changing the line of draft of the machine. These devices consist essentially of a platform supporting a divided pole and connected by parallel bars to a platform of the frame of the machine and connected by a segment rack, pinion and a handle together with locking devices for fixing the predetermined relations of these parts. I further employ improved devices for mounting and supporting the coverers to and from the main axle of the machine and for applying the necessary power for insuring the performance of their function.

My aforesaid features of improvement are herein-after more particularly described.

In the drawing, Figure 1 is a perspective view representing the essential features of the machine of my improvement at the left-hand side. Fig. 2 is a vertical longitudinal section and partial elevation on the dotted line x, x , of Fig. 3. Fig. 3 is a vertical transverse section and elevation on the plane of the axle of the machine. Fig. 4 is a plan and Fig. 5 a side elevation at the forward part of the machine by the divided pole, and by means of which the line of draft of the machine is altered. Fig. 6 is a horizontal section and partial plan view showing the gear devices by which the speed of the pickers is changed. Figs. 7 and 8 are cross sections of the axle and elevations of the clutch device by which the pickers are brought into or thrown out of operation. Fig. 9 is a side elevation and Fig. 10 a plan in larger size showing more in detail my improvements in the coverer devices generally illustrated in Fig. 1.

The parts which are not necessary to my present improvements but which are essentially shown in Fig. 1 and form essential parts of my improved potato-planter comprise the frame 2, the main axle 3, the wheels 4 and 5 mounted on the ends of the main axle, the plow or furrow opener 6 which is supported in an adjustable relation to the frame, the hopper 7 into which the potatoe descend by gravity from the sack hopper and which hopper is supported from the frame and by sleeves 17 which surround the main axle. A seat 8 for a driver is supported upon a seat standard 9 secured to the frame of the machine and 10 represents the coverers at the rear of the potato-planter and the function of which is to deliver the soil over the pota-

toes as deposited so as to form a ridge of earth. 11 represents a divided pole similar to that shown in my aforesaid patent, 13 are the pickers and 14 the concaves in which the pickers take up on their prongs 5 the potatoes to be planted.

a, a¹, represent my improved sack hoppers formed of flexible material of tapering outline largest at the upper end and securely fastened in any desired manner to a strap frame b of metal at their upper ends. 10 As shown in the section Fig. 2, I prefer that the strap frame b have its counterpart inside the frame member or members and I employ bolts passing through said parts and through the sack hoppers to make a tight and secure joint of the parts for supporting the 15 sack hoppers at their upper ends. The strap frame b is supported by vertical frame members b¹, b², generally arranged vertically and at their upper ends bolted to the strap frame b and at their lower ends connected by the bolts b³ to the upper side portions of the magazine 7. The support for these sack hoppers is thus 20 exceedingly rigid and the lower contracted ends of these sack hoppers come within flange prolongations b⁴ of the magazine or receiving hopper. I employ a rocker bar c with trunnion ends in bearing lugs c' 25 which lugs are formed with or bolted to the vertical frame members b¹, b².

d, d, represent the gates which are in the form of vertically elongated metal plates securely connected to the rocker bar c by bolts c² with their lower ends 30 bent at an obtuse angle to the main portions and the sides of the lower ends and bent portion provided with one or more ribbed edges d' which stiffen the same.

Surrounding the main axle 3 between the sleeves 35 17 and extending across within the limits of the receiving magazine 7, is a sleeve 20 forming a part of the picker head and having an eccentric e thereon. A connecting rod e' is provided with a casing e² and the casing surrounds the eccentric e so that with the 40 movement of the axle and the sleeve 20 and picker head, the eccentric imparts a longitudinal or reciprocating movement to the connecting rod e'. A toggle bar f is at its lower end pivotally connected to the upper slotted end of the connecting rod e' and at its 45 upper end said toggle bar is pivotally connected to a lug at the upper end of one of the gates d, and I employ a thumb screw f' passing through this toggle bar and its pointed end reaching to contact with the face of the gate and a spring g is at one end secured to an 50 eye at the upper end of the said toggle bar f and at its other end to an eye upon the fixed seat rod 9. At the lower ends of the gates d, d, are pivoted gravity members h. These are shown in elevation in Fig. 3 and in vertical section in Fig. 2, and the opposite 55 position of the gate to the one shown in full lines in Fig. 2 is indicated in said figure by dotted lines.

The rotation of the main axle 3 and the operation of the eccentric e imparts movement to the connecting rod e' and toggle bar f and against the tension of the 60 spring g a rocking movement to the bar c which is imparted to the gates d, one extreme movement being shown in full lines, Fig. 2, and the other in dotted lines. This causes an agitation of the potatoes in the hopper and provides room for the periodical descent 65 of the potatoes from the sack hoppers into the main

hopper 7. The function of the gravity members h, especially in the dotted position of the parts, being to prevent a too rapid movement or delivery of the potatoes from the sack hoppers to the main hopper. A slot in the upper end of the connecting rod prevents 70 a full return of the gates until the potatoes are partly removed by the pickers, when by action of the spring, they return and by lesser action keep the supply of potatoes uniform. Between the action of the spring g and the thumb screw f', the gates d, d, return according to the quantity of remaining potatoes, once with every rotation of the eccentric e to the initial position shown in Fig. 2.

The supports for the pickers 13 of my improved form are shown particularly in Figs. 2 and 3, in which 80 the three-part low cut heads i are secured to the sleeve 20 at spaced apart intervals and have bolted to them the series of picker devices. While I have shown these picker devices in detail, they *per se*, do not form any part of my present invention over and above 85 the disclosure in my aforesaid patent; the novelty and utility of these heads being in doing away with a possible lodgment or clogging of the potatoes in the hopper, or in other words, preventing the potatoes getting between said heads where they will be liable 90 to lodge and clog and be carried over the front of the machine when planting on downward hilly slopes, as is the case with the construction of these parts as shown in my Patent No. 342,491, and which difficulty 95 the device of my present invention overcomes. 95

Referring particularly to Figs. 3 and 6 the main wheel 4 of the machine is shown as loose upon the axle, being simply held in position by a cap washer and pin upon the end of the axle. In these figures k represents a gear which surrounds a hub of the wheel 4 and which 100 has lugs provided therewith and is secured to the spokes of the said main wheel 4 by eyes and bolts k¹, or in any other convenient manner.

I provide a stud l suitably secured and firmly fastened to the frame 2 of the potato planter and gears l¹ l² 105 mounted upon the said stud and held in position by a ring washer and pin upon the outer end of the stud. The gear l¹ is in mesh with the gear k of the wheel 4 and the gear l² upon this stud l and which comes directly behind the gear l¹ is connected to the gear l¹ by projections which pass into recesses of the said gear l¹ and thus interlock as shown in Fig. 6; said gear l² being in mesh with the gear m mounted upon the main axle 3 and connected thereto by a pin shown in Figs. 3 and 6, the rotary movement and power being communicated from the wheel 4 through the gear k to the gears l¹ l² and by the latter gear l² to the gear m and axle and from the axle through the heads i to the pickers 13 of the series. The gear k is readily removable from the main wheel 4 and is interchangeable with a larger or 110 smaller gear and the gear l¹ on the stud l is also easily removable and is interchangeable with a larger or smaller gear according to the size of the gear secured to the main wheel 4. These gears being interchangeable provide for changing the ratio of speed or rotary movement communicated to the main axle and therefrom to the pickers, that is, the ratio of movement is in proportion to the travel of the potato planter so that the potatoes may be planted nearer together or further apart as 115 desired. 120

For the purpose of connecting the sleeve 20 carrying the eccentric e and the heads i with the pickers 13 of the series to the main axle 3 I have shown and employ a collar n which is pinned to the axle and a clutch shell 5 n^1 which passes over the said collar with a helical spring around the main axle between the inner surface of the shell and the inner face of the collar; the collar being provided on its outer end with a series of teeth as shown in Fig. 8, the said collar and clutch shell being 10 provided with splines shown in Fig. 7 for causing said parts to turn together. One head i as shown in Fig. 3 is provided with a flange and its inner face with opposite teeth to be engaged by the teeth shown in Fig. 8 upon the face of the clutch shell. Normally these parts are 15 in engagement by virtue of the expansion of the said spring. They may however be separated by the action of a lever o , the hub of which surrounds the clutch shell n^1 and the movement of which slides the clutch shell over the collar separating the interlocking teeth 20 which communicate the movement. These devices are to be brought in evidence when the potato-planter is being conveyed from a place of storage to the field or on the return, and during which time it is not desirable to operate the picker devices or the gate devices in connection with the hoppers. 25

Referring particularly to Figs. 1, 9 and 10 in connection with the leverage devices for holding down the coverers 10, these coverers are disks of metal set in converging planes and mounted upon a shaft which in 30 turn is suitably connected to arms 15, as shown in my aforesaid patent, and in the device of my present invention these arms 15 are pivotally connected to lugs 30 on the main axle of the machine and they have connected to them brackets 16 which with the free ends of the 35 arms 15 are also pivoted to the lugs 30, the construction being forked. A yoke-bar 27 which crosses over forward of the seat rod 9, or in other words, which straddles the seat rod and its support is connected at its free ends to the said brackets 16; the parts being secured 40 bolted together, and from one side of this yoke bar extends a handle 18 in operative proximity to the driver so that the hand or foot of the driver may be brought into play either to raise the coverers or to force the same deeper into the soil, and I employ a 45 spring 19 connected at one end to an eye of the vertical frame member b^2 and at its other end to a bracket eye-bar 31 mounted upon the said yoke bar 27. The function of this spring 19 is to draw upon the said yoke bar and convert the same for downward pressure into a 50 lever whose effect is against the arms 15 through the brackets 16 to force the coverers 10 into the soil and to hold them in position to their work. Their function may be augmented by a pull of the hand upon the lever-handle 18 and by pushing down on this handle 55 the coverers may be lifted out of the soil.

Referring now particularly to Figs. 1, 4 and 5, with reference to the devices for preventing the horses walking on the ridge of earth over the previously planted row, I construct the forward end of the frame 2 as tapering and at this forward end I place a bearing bracket r through which passes a short shaft with a pinion r^1 on the lower end of the short shaft and a handle r^2 secured to the upper or projecting end of the short shaft; the pinion being turned by the handle. To this forward end of the frame 2 I secure parallel bars s, s^1 on

pivots 21 near the opposite edges and these bars move over the upper face of the frame 2. Between and to the back ends of the divided pole 11 I secure a platform t preferably of metal and the free ends of the parallel bars s, s^1 are connected at opposite pivots 22 to the said platform t . The platform t is provided at its back edge with a segment rack t^1 , the teeth of which mesh with the teeth of the pinion r^1 . There is a series of holes in the forward portion of the frame 2 and a series of holes in corresponding positions in each of the parallel bars 75 s, s^1 and a locking pin 23 is employed so as to pass through one of the holes either of the bar s or the bar s^1 into one of the holes in the forward portion of the frame 2 so as to lock the hole and platform t in a predetermined relation with the frame 2 and the potato-planting machine. Fig. 4 shows the extreme position and the relation of these parts with reference to one another, and the proportions of the parts are so arranged and formed that when the pin 23 is withdrawn the handle r^2 and pinion r^1 may be rotated so as to move the segment rack t^1 , the platform t and divided pole 11 and swing the same with reference to the frame 2 of the potato-planter upon the parallel bars s, s^1 from the position Fig. 4 nearer to the center or over to the opposite side. 80

Supposing the position, Fig. 4 to be the correct position for use, in passing down and planting a field in one direction, to return and plant the next row especially where the rows are put as close as twenty inches apart, it will be found necessary to swing the divided 95 pole as much to the opposite side of the frame 2 as it is swung to one side as shown in Fig. 4, and with each return over the field the position of the pole is to be changed so that the horses in traveling may not disturb the last made row of potatoes planted. 100

It will be apparent that with the pole thrown to one side as hereinbefore described, that there is a slight side draft and this is compensated for by the position of the bars which are pivoted slightly closer at the front indirectly causing the plow to point slightly toward the side of the line of draft and in this way the machine will run true although possibly it will take a little more power than if running direct and straight ahead. The improved pole device hereinbefore described, forms the subject of a separate application for Letters 110 Patent. 110

I claim as my invention:

1. The combination in a potato planter with a supporting frame, a potato magazine and means for delivering the potatoes to be planted from the magazine, of flexible material sack hoppers of tapering form, a metal frame connected to the upper edges of said hoppers and from which the sack hoppers hang by gravity and vertical frame members secured to the said metal frame at one end and to the frame of the machine at the other end for supporting the said hoppers. 115

2. The combination in a potato planter with a supporting frame, a receiving magazine or hopper and means for delivering the potatoes to be planted from the magazine, of flexible material sack hoppers of tapering form, a metal frame connected to the upper edges of said hopper and from which the sack hoppers hang by gravity, vertical frame members secured to the said metal frame at one end and to the frame of the machine at the other end for supporting the said sack hoppers and means supported in proximity to the said sack hoppers and acting upon the same for regulating the delivery of the potatoes therefrom. 125

3. The combination in a potato planter with the frame, the receiving magazine or hopper associated therewith, the

concaves and the series of pickers, of vertical frame members secured at the sides to the frame of the machine and rising therefrom, a strap frame of metal in an elevated position secured to said vertical frame members and flexible sack hoppers hanging by gravity and located at either side of the concaves and series of pickers, and secured at the upper ends to said strap frame.

4. The combination in a potato-planter with the frame, the receiving magazine or hopper associated therewith, the concaves and the series of pickers, of vertical frame members secured at the sides to the frame of the machine and rising therefrom, a strap frame of metal in an elevated position secured to said vertical frame members and flexible sack hoppers hanging by gravity and located at either side of the concaves and series of pickers, and secured at the upper ends to said strap frame and devices bearing upon said flexible sack hoppers and means for actuating the same for controlling the delivery of the potatoes from said sack hoppers to the hopper adjacent to the concaves and pickers.

5. The combination in a potato-planter with the frame, the receiving hopper associated therewith, the concaves and the series of pickers, of vertical frame members secured at the sides to the frame of the machine and rising therefrom, a strap frame of metal in an elevated position secured to said vertical frame members, flexible sack hoppers hanging by gravity and located at either side of the concaves and series of pickers, and secured at the upper ends to said strap frame, a rocker bar pivoted to the vertical frame members, gates bearing against and secured to the lower inner portions of said sack hoppers and in turn secured to said rocker bar and having lower ends at an inclination to the main connected portions and means for swinging said gates on said rocker bar for controlling the delivery of the potatoes from the sack hoppers.

6. The combination in a potato-planter with the frame, the receiving hopper associated therewith, the concaves and the series of pickers, of vertical frame members secured at the sides to the frame of the machine and rising therefrom, a strap frame of metal in an elevated position secured to said vertical frame members, flexible sack hoppers hanging by gravity and located at either side of the concaves and series of pickers, and secured at the upper ends to said strap frame, a rocker bar journaled in the vertical frame members, gates bearing against and secured to the lower inner portions of said sack hoppers and in turn secured to said rocker bar and having lower ends at an inclination to the main connected portions, devices connected to the upper ends of the said gates and having an adjustable relation to one another and to the gates and a connection therefrom to the main axle of the machine and a spring coacting therewith.

7. In a potato-planter, the combination with a flexible sack hopper and a frame supporting the same, of a rocker bar in trunnions in said frame, a gate in the form of a metal plate secured to said rocker bar and also secured to the flexible sack hopper, a main axle, a head with an eccentric device connected therewith and a connecting rod therefrom, a toggle bar at one end pivoted to said connecting rod and at its other end to a pivotal connection with the upper end of the gate, a spring connected to the upper end of the toggle bar at one end and at its other end to a fixed support and means for adjusting the relation of the said gate, the toggle bar and connecting rod for different degrees of movement.

8. In a potato-planter, the combination with a flexible sack hopper and a frame supporting the same, of a rocker bar in trunnions in said frame, a gate in the form of a metal plate secured to said rocker bar and also secured to the flexible sack hopper, a main axle, a head with an eccentric device connected therewith and a connecting rod therefrom, a toggle bar at one end pivoted to said connecting rod and at its other end to a pivotal connection with the upper end of the gate, a spring connected to the upper end of the toggle bar at one end and at its other end to a fixed support, means for adjusting the relation of the said gate, the toggle bar and connecting rod for different degrees of movement, the said gate plate having a bent lower end at an obtuse angle thereto and provided with one or

more ribbed edges for strengthening and stiffening the same and a gravity member pivotally connected to the lower portion of said bent end, said parts serving to regulate the delivery of the potatoes from the hopper.

9. In a potato planter, the combination with a main axle and surrounding sleeve, of a series of pickers, low-cut heads surrounding and secured to said sleeves and forming supports for the pickers, substantially as set forth, whereby the potatoes are not liable to be caught between the head supports for the pickers.

10. In a potato-planter, the combination with a main axle and a surrounding sleeve, of two spaced apart low cut heads each having three projecting portions surrounding and secured to the sleeve and two series of pickers three in each series secured to said heads and arranged alternately the one to the other, so that there is no liability of the potatoes being caught between the spaced apart heads.

11. In a potato-planter, the combination with a main axle, a sleeve surrounding the same and a series of pickers mounted to revolve with said sleeve, of a driving wheel of the planter loose upon said axle, a gear secured to said wheel, an adjacent gear secured to said axle, a stud upon the frame and superimposed associated gears mounted revolutely upon said stud and meshing with the aforesaid gears whereby the pickers are rotated from said driving wheel through the main axle whereby their speed of rotation is controlled.

12. In a potato-planter, the combination with a main axle and a stud secured to the main frame parallel therewith, of a main wheel loose upon said axle, a gear secured to said wheel, interlocking gears μ , ν upon said stud, the first of said gears meshing with the gear k , a gear m back of the gear k and secured to the axle and meshing with the gear ν ; the gears k , μ , ν , being removable and interchangeable with other gears, whereby the rotation and power of the main wheel is communicated and transferred to the axle and its ratio of rotation controlled.

13. In a potato planter, the combination with means for holding and means for delivering potatoes upon the ground, and coverers for covering the same with earth, and an axle for said coverers, of the arms 15 extending from the said axle, the brackets 16 connected with a fixed part of the machine and to which the arms 15 are secured, the yoke-bar 27 connected at its free ends to said brackets and a spring 19 secured at one end to a fixed part of the machine and at its other end to the said yoke-bar 27, said connection being at a point distant from the coverers for increased leverage and more perfect control.

14. In a potato planter, the combination with means for holding and means for delivering potatoes upon the ground, and coverers for covering the same with earth, and an axle for said coverers, of the arms 15 extending from said axle, the brackets 16 connected with a fixed part of the machine and to which the arms 15 are secured, the yoke-bar 27 connected at its free ends to said brackets, a spring 19 secured at one end to a fixed part of the machine and at its other end to the said yoke-bar 27, said connection being at a point distant from the coverers for increased leverage, and a handle 18 forming a substantial prolongation of the yoke-bar 27 forward of the same and adjacent to the position of the operator.

15. In a potato planter, the combination with means for holding and means for delivering potatoes upon the ground, coverer disks for covering the same with earth, and an axle for and extending between the said coverers, of the arms 15 extending from connections with the said axle, lugs 30 upon the main axle sleeve, brackets 16 secured to the arms 15, pivot pins securing the brackets 16 and the free bent ends of the arms 15 to the said lugs 30, a yoke-bar 27 connected at its free ends to the brackets 16 and crossing over the forward part of the machine, a handle 18 and bracket eye-bar 31 secured to the yoke-bar 27, and a spring 19 connected at one end to the bracket eye-bar 31 and at its other end to a fixed part of the machine.

Signed by me this second day of April 1906.
